(57) CLAIM

The ornamental design for an oral care display package, as shown and described.

DESCRIPTION

FIG. 1 is a perspective view of an oral care display package, showing our new design;

FIG. 2 is a right-side elevation view thereof;

FIG. 3 is a rear elevation view thereof;

FIG. 4 is a left-side elevation view thereof;

FIG. 5 is a front elevation view thereof;

FIG. 6 is a top plan view thereof; and,

FIG. 7 is a bottom plan view thereof.

The grayscale shading of the oral care display package represent a contrast in appearance. In the drawings, the evenly-spaced broken lines depict portions of the oral care display package that form no part of the claim.
